TISSUE PACKET

Dorothy Lee Pelton, St. Louis, Mo.

Application October 7, 1949, Serial No. 5,347

Term of patent 3½ years

(Cl. D58—2)

To all whom it may concern:

Be it known that I, Dorothy Lee Pelton, a citizen of the United States, and a resident of the city of St. Louis, State of Missouri, have invented a new, original, and ornamental Design for a Tissue Packet, of which the following is a specification, reference being had to the accompanying drawing, forming a part hereof.

Fig. 1 is a perspective view of a tissue packet showing my new design.

Fig. 2 is a top plan view thereof,

Fig. 3 is a bottom plan view, and

Fig. 4 is an end elevational view showing the end opposite to that shown in Fig. 1.

I claim:

The ornamental design for a tissue packet, substantially as shown.

DOROTHY LEE PELTON.
